(57) **CLAIM**

The ornamental design for a container for volatilizing chemicals, as shown and described.

DESCRIPTION

FIG. 1 is a perspective view of a container for volatilizing chemicals showing our new design;

FIG. 2 is a front view thereof; the rear view being a mirror image thereof;

FIG. 3 is a right side view thereof;

FIG. 4 is a left side view thereof;

FIG. 5 is a top plan view thereof; and,

FIG. 6 is a bottom plan view thereof.

The top of the container is open, with any structure shown therein being illustrated with broken lines and not forming any part of the claimed design.
